UNITED STATES PATENT OFFICE.

FRANK M. PIERCE AND ALBERT C. WARNER, OF ALLENTEWON, ILLINOIS.

WAGON END-GATE.

SPECIFICATION forming part of Letters Patent No. 593,813, dated November 16, 1897.

Application filed March 22, 1897. Serial No. 628,628. (No model.)

To all whom it may concern:

Be it known that we, FRANK M. PIERCE and ALBERT C. WARNER, citizens of the United States, residing at Allentown, in the county of 5 Tazewell and State of Illinois, have invented certain new and useful Improvements in End-Gates; and we do hereby declare that the following is a full, clear, and exact description of the invention, which will enable others 10 skilled in the art to which it appertains to make and use the same.

Our invention relates to certain new and useful improvements in end-gates for wagon-beds, by means of which a simple means is 15 provided for connecting the end-gate with a wagon-bed that is simple and easy in manipulation and well adapted for the purpose designed.

More particularly our invention relates to 20 an end-gate adapted to be attached to the wagon-bed without making any positive bolt connections that will in any way mar or deface the same.

Our invention consists of a hanger-plate 25 adapted to engage the side of the bed, bearing over the edge thereof, and its outside depending portion carrying the necessary parts to be engaged by parts that are likewise connected with the end-gate, a bar having a pivotal connection with the said plate and with the end-gate and readily detachable from each and provided with sets of perforations adapted to facilitate in shortening or lengthening the connection between the said plate and the 30 end-gate to accommodate its connection with any height of wagon-bed, the end-gate having side pieces of sheet metal or other suitable material, a loop secured at each side of the end-gate and in connection with the side 35 pieces and so connected as to render the same adjustable thereon, a link engaging the said loop, a rod engaging the link and provided with a hook at its free end, the said rod adapted to be carried in an eye or lug upon 40 the plate and the hook adapted to engage the said eye or lug and the side pieces of the end-gate provided with hooks or lugs adapted to engage the said rod, and of other minor details of construction hereinafter particularly mentioned.

That our invention may be more fully understood reference is had to the accompanying drawings, in which—

Figure 1 is a side elevation showing our devices applied to a wagon-bed and an end-gate. 55 Fig. 2 is also a side elevation showing the same parts, but in a different relative position. Fig. 3 is a detail view of the hanger-plate. Fig. 4 is a detail view showing one side of the end-gate as it is viewed from the 60 rear end. Fig. 5 is a detail view of the connecting-bar. Fig. 6 is a detail view.

In the drawings, A is the wagon-body, which is provided with the usual cleats at its rear end, which are indicated by the dotted lines. 65

B is the end-gate. The end-gate may be made of any suitable material, but we prefer to make the bottom portion thereof out of wood and the side pieces of sheet metal, and we provide the side pieces with the hooks b, which 70 are formed simply by bending down small extensions provided on the side pieces, as plainly shown in the drawings, but in case wooden side pieces are used any suitable hook or lug may be provided, the said hooks being 75 adapted to engage the rods when the end-gate is raised, as shown in Fig. 2.

C is a plate which serves as a hanger, the detail construction of which is shown in Fig. 3. This hanger is adapted to be carried over 80 the edge of the wagon-bed, as shown in the figures, and the portion that depends on the inside of the bed is adapted to bear against the cleat, as shown, and it is provided with one long straight edge adapted for this bearing, as shown in the detail.

c is a pin projection from the lower end of that portion of the hanger-plate that depends on the outside of the wagon-bed, and it is provided with a small tapering projection from 90 its outer end, which extends laterally therefrom.

D is a bar provided with the sets of perforations d d d d, the perforations of each set opening into each other, as shown, and are 95 adapted to be engaged by the pin c on the hanger-plate.

E is a plate secured to the rear end of the end-gate and at its outer edge and is provided with a pin-formed projection, which said pro- 100

jection has a laterally-extending tapering lug at its outer end, the pin-formed portion of the plate being adapted to engage an opening in the end of bar D, having the shape as shown in Fig. 5 and indicated by e, the lug on pin projection from plate E being so directed and the opening in bar D being so placed that in order that the parts may be caused to engage each other the end-gate will have to be lowered to a position below the plane of the bottom of the wagon-bed, and when such engagement is made and the end-gate is raised slightly or to any degree of elevation the parts cannot become disengaged. We provide the sets of perforations d in order that we may connect the end-gate with any wagon having any height of bed and without regard to the different widths of cleats on different wagon-beds. The connection of the bar D with the pins c on the hanger-plate C is made in the same manner as the connection is made of the bar with the end-gate—that is, the bar D can only be placed upon the pin when disengaged from the end-gate and turned into a certain position, and when such engagement is made of the parts and the bar is connected with the end-gate then the bar cannot be disengaged from pin c no matter what the adjustment of the end-gate may be. To accommodate the connection with low or high sides of the wagon-bed and to accommodate the different distances the cleats are placed from the end of the bed, we simply make the connection of the pins c with the proper perforation in bar D, after the hanger-plate C has been properly placed, that will cause the end-gate to be supported at the proper height, in this manner providing a very simple arrangement of parts to facilitate the adjustment of our devices in connection with any wagon-bed.

F is a loop adapted to be carried above the edge of the side piece of the end-gate, and we connect one of the depending ends of the loop with the bottom of the end-gate by means of screw-thread and nut, as shown, and the other end of the loop is flattened out and slotted and is connected with the side piece by means of a bolt. This loop may be raised or lowered in order to harmonize the adjustment of the shoveling-board as to pitch when connected with different wagon-beds having varying heights.

G is a link engaging the loop and is preferably made with a slight curve.

H is a rod connected with the link and provided with the laterally-extended lugs h, that bear on the link, and with a hook at its free end, the said rod being adapted to be carried in the eye or lug I on the hanger-plate and is adapted to be engaged by the hook on the rod when the end-gate is lowered and serve as a support for the end-gate.

In the above description we have referred to a single set of devices and parts as they are carried upon one side of the wagon-bed and upon one side of the end-gate, but of course

it will be understood that a duplicate set is arranged upon the opposite side and that it is necessary that both sets be used in carrying out the invention.

The parts having been placed in their relative positions shown in the drawings, the end-gate will be supported in its lowered position in the manner shown in Fig. 1, in which case the end-gate will be supported at its lower end by bar D engaging both the hanger-plate and the end-gate and will be supported from its upper edge by means of the rod H engaging the eye or lug I on the hanger-plate. The end-gate will be supported in position to close the rear end of the wagon-bed in the manner shown in Fig. 2, in which it will be seen that the rod H has passed through the eye or lug I and that the curved link G is carried through the said eye or lug and upon its lower edge and that the said rod H is engaged at its lower end by the hook b on the side piece of the end-gate, the said link G being curved to provide a more positive bearing in the eye or lug I. The link G has quite an extensive scope in its connection with loop F, which is necessary, and the loop is formed so as to provide for this adjustment, so that when the end-gate is connected with a high wagon-bed, which will necessarily carry the hanger-plate at a considerable height, the link G may move toward and, if necessary, to the extreme upper end of the said loop, and when the said parts and the end-gate are connected with a low wagon-bed, which will carry the hanger-plate in a lower position from that just referred to, then the link adjusts itself automatically at a lower point in the loop, as will plainly be seen without further explanation. Attention is called to Fig. 6, which shows the manner in which the lugs h bear upon the link, which will prevent the toggle-joint from buckling downward when the end-gate is pushed up to close the end of the wagon-bed, and by means of these lugs being provided to bear upon the link in the manner shown when the end-gate is raised the rod will be pushed straight ahead until the link enters loop I, at which time the rod will drop down in readiness to be engaged by the hooks b on the sides of the end-gate.

Having thus fully described our invention, what we claim, and desire to secure by Letters Patent, is—

1. In an end-gate for wagons, the combination of the hanger-plate C, provided with the loop I and the pin c having a laterally-extending lug therefrom; of the bar D, provided with the sets of perforations d and with an elongated perforation at one end thereof adapted to engage a pin or lug on the end-gate; the rod H, having a toggle-joint connection with the loop F on the end-gate and provided with a hook on its free end adapted to engage the loops I on the hanger-plate when the end-gate is lowered, the said rod H adapted to be engaged by the lug b on the end-gate.

when the end-gate is in an elevated position, substantially as and for the purpose described.

2. In an end-gate for wagons, the combination with the wagon-body, of the hanger-plate C, provided with the loop I, and the pin c; the end-gate B, provided with the adjustable loop F; the bar D, provided with sets of perforations d, adapted to be engaged by pin c, and provided with a perforation at one extremity for engaging a lug or pin on the end-gate; the rod H connected with the loop F, by means of the link G, and provided with the lugs h, bearing on the link, and having a hook on its free end adapted to engage the loop I, on the hanger-plate when the same is lowered, the said rod H, adapted to be engaged by the lug b, on the end-gate when the end-gate is in an elevated position, substantially as and for the purpose described.

3. In combination with a wagon-body, an end-gate provided with the adjustable loop F, the hanger-plate C provided with the loop I, and the pin c, the bar D, provided at one extremity with an elongated slot e, engaged by

the pin E, on the end-gate, and having a series of perforations d, throughout its length for engaging the pin projection on the hanger-plate adapting the end-gate to any height 25 of wagon-bed, the rod H, connected to the loop on the end-gate through and by means of the link G, and provided with the lugs h, bearing on the link, and having a hook on its free end adapted to engage the loop I, on the 30 hanger-plate when the same is lowered, the said rod H, adapted to be engaged by the lug b, on the end-gate when the end-gate is in an elevated position, substantially as and for the purpose described.

In testimony whereof we affix our signatures in presence of two witnesses.

FRANK M. PIERCE.

ALBERT C. WARNER.
